GEORGE L. BEERS, OF WILKINSBURG, PENNSYLVANIA, ASSIGNOR TO WESTINGHOUSE ELECTRIC & MANUFACTURING COMPANY, A CORPORATION OF PENNSYLVANIA.

RADIO RECEIVING SYSTEM.

Application filed February 10, 1925. Serial No. 8,208.

My invention relates to radio receiving systems and particularly to radio receiving systems comprising loop antennæ.

It is an object of my invention to construct 5 a radio receiving system provided with loop antennæ and having means for preventing the re-radiation of local oscillatory energy from the loop.

Another of my invention is to construct a 10 radio receiving system comprising a loop antenna, and superheterodyne receiving apparatus in which the re-radiation of the oscillations of the local heterodyne oscillation generator is effectually prevented.

15 In the operation of radio receiving systems adapted to be combined with a loop antenna, difficulty has been experienced with the re-radiation of oscillatory energy from the loop, especially when the connected apparatus is 20 of the superheterodyne type having a local oscillation generator therein.

My invention provides means whereby the introduction of local oscillations in the loop antenna is compensated for and the radiation 25 of energy therefrom is prevented.

Other objects and structural details of my invention will be apparent from the following description when read in connection with the accompanying drawings, wherein:

30 Figure 1 is a diagrammatic representation of circuits and apparatus embodying a preferred form of my invention, and

Fig. 2 is a diagrammatic representation of an alternative embodiment.

35 Referring to Fig. 1, a loop antenna 1 is connected to a triode 2. The loop 1 has connected across the terminals thereof a tuning condenser 3. One of the terminals of the loop 1 is connected to the grid of the triode 2. 40 The other terminal of the loop 1 is connected through a balancing condenser 5 to the anode of the triode 2. A parallel resonant circuit 4 is connected to one terminal of the cathode of the triode 2 and is also connected to a mid-point of the loop 1.

45 In the anode circuit of the triode 2 is connected an inductance device 6 which is inductively related to the inductance of the parallel resonant circuit 4. From the coil 6, 50 the anode circuit of the triode 2 is connected to the primary of an oscillation transformer 7, the secondary of which is connected to an amplifying triode 8 which, in turn, is connected through the second oscillation trans-

former 9 to a detector triode 11 and signal translating means 12.

In the operation of the system, incoming signal energy causes the resonant circuit, comprising the loop 1 and the condenser 3, to oscillate when the natural resonant period of 60 the system is substantially the same as that of the incoming signals. The resonant oscillation thus produced, develops potential differences across the condenser 3 and across the terminals of the loop 1. One-half of the 65 developed potential is impressed between the grid and cathode of triode 2 by way of the grid connected end of the loop 1 and the midpoint, through the parallel resonant circuit 4.

The presence of the circuit 4 and the coil 6 inductively associated therewith provides the combination of circuits needed for the production of self-oscillation of the triode 2. The frequency of this self-oscillation is determined by the natural resonant frequency of 75 the circuit 4 which may be made different from the frequency to which the combination of the loop 1 and condenser 3 are tuned, thereby producing beat phenomena when combined with the signal oscillations. These 80 beat phenomena are resolved by the triode and associated circuits into oscillations of a different radio frequency which is the same as the beat frequency, and which are modulated similarly to the original signals and 85 are adjusted to occur in the system at the frequency to which the oscillation transformer and triode 8 are tuned.

The tuning of the resonant circuit 4 should desirably be such that its fundamental frequency is one-half of the frequency required to heterodyne the incoming signals for the production of the desired beat frequency. The harmonic of the fundamental frequency of the generator then heterodynes the incoming signals in the usual way. This use of the harmonics has been found desirable in order to prevent improper reaction between the stray fields of the loop antenna 1 and the resonant circuit 4 which tend, when the fundamental frequency is used, to develop troublesome interfering frequencies that make the operation of the device less certain.

90 95 100 105 The beat oscillations are amplified in the customary way, detected by triode 11 and its associated circuits and translated into sound by receivers 12.

The triode 2 is set into self-oscillation by

energy transferred from coil 6 through circuit 4 and the midpoint of loop 1, half of the turns of loop 1, to the grid of triode 2. This energy, however, is susceptible to re-radiation therefrom. The presence of a connection between the other terminal of loop 1 and anode of triode 2 results in a path for energy through the other half of the turns of loop 1, to the grid of triode 2.

10 By making the capacitance of the balancing condenser 5 substantially equal to the capacitance between the grid and the cathode of the triode 2, substantially equal amounts of energy are allowed to flow through both halves of the loop 1. These equal increments of energy flow in opposite directions through loop 1, are substantially 180 degrees out of phase and the magnetic fields produced thereby in loop 1 are substantially neutralized and, 20 thereby, no radiation therefrom occurs.

In the alternative embodiment shown in Fig. 2, a separate oscillation generator is provided, consisting of a triode 13, a resonant circuit 14 coupled to a plate coil 15, and 25 an output coil 16. The coil 16 is coupled to a coil 17, which is substituted for the circuit 4 of Fig. 1 and is connected between the center tap of the loop 1 and the cathode circuit of the triode 2. The system of Fig. 2 operates 30 in a similar manner, except that the oscillatory energy is furnished by the local generator comprising the triode 13 instead of by the self oscillation of the triode 2.

While I have shown but two embodiments 35 of my invention in the accompanying drawing, it is capable of various changes and modifications therefrom without departing from the spirit thereof, and it is desired, therefore, that only such limitations shall be placed 40 thereon as are imposed by the prior art or indicated in the appended claims.

I claim as my invention:

1. A radio receiving system, comprising a loop antenna having a plurality of turns of 45 conductor and three terminals connected respectively to the ends of said conductor and a point therein near the center thereof, a tun-

ing condenser connected to the said end terminals, a repeater triode, the grid thereof being connected to one of said end terminals, 50 the cathode being connected to said center terminal, and the anode being connected to the other of said end terminals, a condenser interposed between said anode and said end terminal, oscillation producing means adapted to produce a frequency different from that to which said loop antenna and condenser are tuned, said means including a device for impressing an electromotive force across a portion of the connection to said center terminal, 55 whereby beat frequency phenomena with received signals are produced, and amplifying and detecting means adapted to strengthen said beat frequency phenomena and translate them into signals.

2. In a radio receiving system, a signal-receiving antenna comprising an inductance, an oscillation generator adjusted to generate oscillations of different frequency from those impressed upon the antenna by the signal and 70 connections whereby the oscillations from said oscillation generator are caused to flow through two portions of said inductance in parallel.

3. A radio receiving system comprising a 75 loop-antenna, a thermionic device having cathode, grid and plate electrodes, a connection from one terminal of said loop antenna to said grid, a connection including a stopping condenser between the other terminal of 80 said loop antenna and said anode, a connection between an intermediate point on said loop-antenna and said cathode, an oscillation generator, and means whereby said oscillation generator may impress potentials between said intermediate point and said cathode, whereby beat-phenomena may be caused between incoming signals and the generated oscillations without permitting the radiation 85 of said oscillations by said loop-antenna.

In testimony whereof, I have hereunto subscribed my name this 3rd day of February, 1925.

GEORGE L. BEERS.
